HEATER UNIT

William J. Russell, Mansfield, Ohio, assignor to
Westinghouse Electric & Manufacturing Company, East Pittsburgh, Pa., a corporation of Pennsylvania

Application October 20, 1939, Serial No. 300,363

8 Claims. (Cl. 219—37)

My invention relates to heating units and more particularly to an easily cleanable surface unit for electric ranges, and is an improvement over my copending application, Serial No. 264,775, filed March 29, 1939, and assigned to the assignee of this application.

An object of my invention is to provide a range surface unit having a supporting pan structure which may be easily and readily removed for cleaning purposes.

A further object of my invention is to provide a range surface unit having means associated therewith which may be easily grasped for ready removal of the unit from a range platform or the like.

Another object of my invention is to provide a range surface unit including a pan structure and heating element having means for lifting and retaining such unit in an elevated position, the pan structure being adapted to support the unit and catch any extraneous matter passing beneath the element when the unit is in its normal operating position, and adapted to be easily removed for cleaning purposes when the unit is in an elevated position.

Other objects of my invention will either be pointed out specifically in the course of the following description of a device embodying my invention, or will be apparent from such description.

In the accompanying drawings,

Fig. 1 is a view partially in section and partially in elevation of a unit embodying my invention resting upon a supporting platform in its normal operating position;

Fig. 2 is a view similar to Fig. 1 with the unit in an elevated position upon the platform;

Fig. 3 is a sectional view taken along the line III—III of Fig. 1;

Fig. 4 is a perspective view illustrating the method of removing the supporting pan structure from the heating element;

Fig. 5 is a view partially in section taken along the line V—V of Fig. 3;

Fig. 6 is a view taken along the line VI—VI of Fig. 1;

Figs. 7 and 8 are views partially in section taken along the line VII—VII of Fig. 3;

Fig. 9 is a side elevational view illustrating an additional method of retaining the unit in an elevated position and of removing the supporting pan therefrom; and

Fig. 10 is a view similar to Figs. 1 and 2 illustrating a modified method of supporting the unit upon a platform.

Referring to the accompanying drawings, in which like reference characters indicate like parts in several figures, I show a range surface unit 10 including a heating element 12, a supporting pan structure 14 adapted to support the heating unit 10 on a range platform, hot plate surface, or the like, 16, during the normal operation of such unit, an elevating supporting structure 18 adapted to support the unit above the platform when it is desired to clean such unit, and a lifting bracket 20 which may be used to lift the unit out of the supporting platform.

The heating element 12, in this instance, comprises an open grid formed of two sheathed members arranged in a spiral in a well known manner. The sheathed members each comprises a resistor 20 embedded within a suitable insulating member 22 and surrounded by a metal sheath 24 in a well-known manner. The insulating material 22 is preferably magnesium oxide or the like and may be positioned within the metallic sheath or envelope 24 in a powdered form. The metallic sheath is formed of any suitable material which will permit the heating element 12 to operate satisfactorily at a high temperature corresponding to red heat.

The sheath members are in this instance formed into two separate substantially concentric spirals and may be either of similar or varying 30 wattages. The substantially concentric spirals are mounted in and attached to suitable radially extending transversely grooved supporting arms 26 in a well known manner. These arms 26 are adapted to support the heating element 12 within 35 in the pan structure 14 in a manner hereinafter described.

It is to be understood that the heating element 12 described herein and illustrated in the accompanying drawings is used primarily for illustrative purposes and other suitable heating elements 40 may be used in lieu thereof.

The ends of tubular sheath members extend 45 downwardly from the main plane of the heating element 12 and pass through a U-shaped terminal shield support bracket 28 and a terminal shield 30 so as to cooperatively engage an insulating terminal block 32 as hereinafter described. The U-shaped terminal shield supporting bracket 28 is in this instance formed from a single sheath of metal and is relatively narrow with respect to its length. The U-shaped support includes a horizontally extending bottom 34 and upwardly extending end portion 36 located at either end thereof.

Apertures 38 are located within the horizontal

bottom portion 34 to permit the depending end portions of the heating element 12 to pass therethrough. Upwardly extending collars or sleeves 40 are integral with the U-shaped supporting bracket and are positioned about the apertures 38 for providing means for rigidly attaching the U-shaped supporting bracket to the depending end portions of the element 12. The upwardly extending end portions 36 of support bracket 28 are shaped substantially the same as the upstanding walls of the pan structure 14 herein-after described and have an outwardly extending flange 42 located at the upper end thereof. The flange 42 and upwardly extending end portions 36 are adapted to rest upon and be substantially in juxtaposition with the side of the pan structure 14 as hereinafter described.

The terminal shield 30 is, in this instance, formed from a single sheet of metal and has an upwardly extending elongated hollow portion 44 having substantially a rectangular shape. (See Fig. 2.) The shield 30 is open at the bottom to enable a terminal block 32 to be associated therewith. Downwardly extending flanges 46 are located at either end of the upwardly extending main portion 44 and are functionally integral therewith. A top portion 48 is formed integral with the upwardly extending portion 44. A plurality of apertures 50 are located therein for permitting the free passage of the downwardly extending heating element 12 to pass therethrough.

The horizontal extending upper portion 48 of the terminal shield 30 is, in this instance, spot or protrusion welded to the lower surface of the U-shaped supporting bracket 28 in a well known manner. The terminal shield 30 and bracket 28 thus are adapted to form a functionally integral rigid structure.

The space located within the upwardly extending portion 44 and below the horizontal portion 48 affords means for locating a suitable terminal block 32 as well as insuring the prevention of spillage or sloppage which may be passed through the heating element 12 from encountering the terminal ends of the depending end portions of the heating element 12.

Suitable notched supporting brackets 18 may be rigidly attached to the depending end portions 36 of the terminal shield 30 to afford means for retaining the heating unit 10 in an elevated or cleaning position substantially as hereinafter described, (see Figs. 2 and 4). However, it is to be understood that the unit need not have associated therewith the brackets 18, but may be manually retained in an elevated position as hereinafter described.

The upwardly extending collars 40 located about the apertures 38 positioned within the horizontally extended surface 44 of the U-shaped bracket 28 may be swedged or pressed tightly against the metallic envelope 24 of the heating element 12 to afford means for rigidly connecting the heating element 12 to the U-shaped bracket 28. It is therefore obvious that with the heating element 12, U-shaped supporting bracket 28 and terminal shield 30 rigidly attached together into a substantially functionally integral structure, such structure will move as a unitary member.

The pan structure 14 comprises, in this instance, a shallow pan having a substantially flat bottom portion 52 with a rectangularly shaped diametrically extending slot 54 located therein and upstanding side portions 56 having an inter-

mediate outwardly extending intermediate ledge 58 formed therein and an outwardly extending flange 60 located about the upper edge thereof. The pan 14 is in this instance formed from a single sheet of metal; however, it is to be understood that such structure may be formed in any other suitable manner.

The diametrically extending slot 54 extends inwardly from one edge of the pan structure and is located within both the bottom portion 52 and a single adjacent side portion 56. The diametrically extending slot 54 is slightly wider than the upwardly extending main portion 44 of the terminal shield 30 so as to permit the pan structure to readily pass along such terminal shield 30.

The outwardly extending intermediately positioned ledge 58 is adapted to support the heating element 12 by means of the radially extending arms 26. The ledge 58 is positioned within the side walls 56 at such a point that the top surface of the heating element 12 will be located slightly above the outwardly extending flange 60 of the pan structure 14 when the arms 26 rest thereon. (See Figs. 1 and 5.)

The outwardly extending flange 60 located about the upper edge of the pan structure 14 has a downwardly extending lip 62 integral therewith to afford means of retaining the pan structure 14 upon the range platform or a hot plate surface 16, in a well known manner.

It is therefore obvious that with the pan structure 14 resting upon the supporting platform 16 that the radially extending arms 26 resting upon the intermediate ledge 58 are thus capable of supporting the heating element 12 in substantially the plane of such supporting platform.

A suitable downwardly extending boss 64 is located within the outwardly extending flange 60 of pan 14 substantially in line with the diametrically extending slot 54 to afford cooperation with the ledge 42 of the U-shaped supporting bracket 28 as hereinafter described.

Pan structure 14 is adapted to easily slide along the terminal shield 30 and upwardly along the end portions 36 of the U-shaped bracket 28 to permit such pan structure to be operatively associated with the heating element and associated structures so as to form a workable unit. The overhanging flange 42 in the U-shaped supporting bracket 28 thus is adapted to rest within the downwardly extending boss 64 at one end and to fill the corresponding gap within the flange 60 and the pan structure 14 at the other end. The flanges 42 thus cooperate with the flange 60 of the pan structure 14 to form substantially a uniform surface about the upper edge of such pan structure 14 as the heating unit rests upon a suitable supporting platform.

Suitable elongated bosses 66 extend substantially parallel to the slot 54, one on either side thereof, and upwardly within the side portions of the pan. These bosses are positioned within the pan structure 14 so as to strengthen or reinforce it. The bosses 66 formed within the bottom 54 and upstanding side portions 56 thus tend to prevent the pan structure from warping as the operator removes it from the heating element and from bending as such pan is cleaned.

A centrally located plate 72 is positioned within the spiraled heating element. The plate 72 is rigidly attached to the radially extending arms 26 and is positioned slightly below the plane of element 12. (See Figs. 3, 4, 7 and 8.) Suitable

slots 74 are located therein for permitting a U-shaped retractable bracket 70 to be attached thereto. The retractable bracket 70 is an elongated relatively narrow ribbon-like member formed into an inverted U-shaped structure. The depending legs of such U-shaped member pass through the slots 74. Outwardly extending lips or flanges 76 are located upon the lower ends of such legs, for limiting the upward travel of such bracket with respect to the plate 72. This feature permits the bracket 70 to be easily grasped and moved in a vertical direction. However, the lips 76 limit the relative movement of such bracket 70 with respect to the plate 72. The slidably mounted bracket 70 may thus be used by an operator as means for lifting the heating unit from the supporting platform.

When it is desired to clean the pan structure 14 of a heating unit 10 positioned upon a range surface or supporting platform, the operator may place her finger, for example, under the vertically movable U-shaped retractable bracket 12 and apply an upwardly extending pressure thereupon. This in turn lifts the heating unit from the supporting platform 16.

Assuming that the unit has the supporting brackets 18 associated therewith, such unit must be slightly tilted so as to permit one of the supporting brackets 18 to pass outwardly above the platform 16. The second bracket may then be positioned so that the notched portions thereof will rest upon the platform 16, whereupon the first supporting bracket 18 may be lowered upon the other side of the supporting platform 16 to support the heating unit 10 in an elevated or cleanable position above the supporting platform.

As the heating unit 10 is lifted out of the supporting platform 16, the pan structure 14 will tend to remain in its original position. However, as the unit 10 is lifted a suitable distance, the lower portion of the terminal shield 30 engages the bottom portion of the pan structure 14 and lifts such pan structure with the unit so that the pan structure will rest thereon. The pan structure 14 is thus positioned somewhat below the heating element 12 when the unit is in its elevated or cleanable position to permit such pan to be easily removed therefrom. The operator may then grasp the pan structure 14 and readily slide such structure along the longitudinal axis of the terminal shield 30 and diametrically extending slot 54 whereby such pan structure may be readily removed from the heating unit. The pan may then be taken to a suitable dishpan, or the like, and be thoroughly cleaned.

While the heating unit is in an elevated position above the platform the operator may if desired thoroughly clean the heating element 12 and associated parts such as the U-shaped supporting bracket 28 and the terminal shield 30. The pan structure 14, after being cleaned, may

be readily slid back into engagement with the heating element with the slotted portion 54 passing along the longitudinal axis of the terminal shield 30. The pan structure 14 will thus rest upon the terminal shield 30 as hereinabove described. The operator may then grasp the vertically movable centrally located bracket 70 and slightly raise the heating element 10 so as to free the right end supporting bracket 18 from the supporting bracket 16. The unit 10 may then again be slightly tilted so as to permit the second supporting bracket 18 to pass through the opening within the platform 16 and to permit heating

unit 10 to be lowered downwardly within such opening.

Before reaching its lowermost position the downwardly extending lips 62 of the outwardly extending ledge 60 of the pan structure 14 contacts the supporting structure 16, thereby retaining the pan in its normal operating position upon the supporting structure. The radially extending arms 26 may then rest upon the outwardly extending intermediately located ledge 58 so as to permit the heating element 12 to rest upon the supporting pan structure 14, substantially in the plane of the supporting platform.

If it be desired, the surface unit 10 may be constructed without having the supporting brackets 18 associated therewith. Such a unit will operate in a manner hereinabove described. However, the operator must hold the unit in an elevated position above the platform by means of the bracket 70 in order to remove the pan structure (see Fig. 9).

Upon removing the pan structure 14, the unit should be lowered down into the supporting platform 16. The outwardly extending flanges 42 of the upwardly extending end portions 36 of the terminal shield bracket 28 then rest upon the platform 16 to support the unit (see Fig. 10).

To replace the pan structure 14, the unit is again lifted by bracket 70 whereupon the pan may readily be slid into place about the element, as hereinabove described.

It is, therefore, obvious that the heating unit 10 embodying my invention as hereinabove described, includes a supporting pan structure which is adapted to catch and retain any and all extraneous sloppage or spillage which may pass through the heating element 12, and is adapted to support the heating element 12 when in its normal operating condition. In addition, such structure may, if desired, include means for retaining the unit in an elevated position so as to permit the supporting pan structure 14 to be readily removed from the heating element whereby such pan structure and element may be thoroughly cleaned.

Various other modifications may be made in the device embodying my invention without departing from the spirit and scope thereof, and I desire, therefore, that only such limitations shall be placed thereon as are imposed by the prior art and the appended claims.

I claim as my invention:

1. In a heating structure for a range platform, the combination of a substantially circular heating element having a flat heating surface and depending terminal portions, a unitary pan comprising a circular side wall and a flange projecting radially outward from the upper end of the side wall and a bottom wall extending across the lower end of the side wall, said flange encompassing the heating element and removably engaging the range platform for supporting the pan in normal position, said pan being provided with a slot extending diametrically inwardly through the flange, side wall, and bottom wall of the pan and said slot terminating in the bottom wall of the pan, and a shield secured to the depending terminal portions of the heating element, said shield being formed to close the slot in the bottom wall of the pan whereby the shield and pan define a complete, heat-reflecting drip receptacle, and said pan being removable from the heating element and the terminal shield in the direction of the slot when the heating ele-

ment and shield are raised above their normal working positions.

2. In a heating structure for a range platform, the combination of a substantially circular heating element having a flat heating surface and a plurality of terminals depending from the heating surface and aligned diametrically thereof, a unitary pan including a dished bottom portion disposed below said heating surface and a flange projecting radially outwardly from the dished bottom portion of the pan, said flange encompassing the heating element and removably engaging the range platform for supporting the pan in normal operation, said pan being provided with a slot extending diametrically inwardly through the flange and bottom portion of the pan and terminating in the latter, a shield connecting said depending terminals and extending diametrically of the heating element, said shield being formed to close the slot in the dished bottom portion of the pan, whereby a substantially uninterrupted, heat-reflecting drip receptacle is defined, said pan being removable from the heating element and the terminal shield in the direction of the slot when the heating element and shield are raised above their normal working positions.

3. In a heating structure for a range platform, the combination of a substantially circular heating element having a flat heating surface and a plurality of terminals depending from the heating surface, a shield connecting said depending terminals and extending generally diametrically of the heating surface, a unitary pan including a circular side wall and a flange projecting radially outward from the upper end of the side wall and said pan including a bottom wall extending across the lower end of the side wall, said flange encompassing the heating element and removably engaging the range platform for supporting the pan in normal operation, said pan being provided with a slot extending diametrically inwardly through the flange, side wall and bottom wall of the pan for receiving said terminal shield, and said slot terminating in the pan adjacent the end of said shield farthest removed from the open end of the slot, said shield closing the slot in the bottom wall and defining with the bottom wall a substantially uninterrupted, heat-reflecting drip receptacle, said pan being removable from the heating element and the terminal shield in the direction of the slot when the heating element and shield are raised above their normal working positions.

4. In a heating structure for a range platform, the combination of a substantially circular heating element having a flat heating surface and terminal portions depending therefrom and arranged generally diametrically of the heating element, a unitary pan including a dished bottom portion extending beneath the element and a flange projecting radially outwardly from the upper end of the dished bottom portion and removably engaging the range platform for supporting the pan in normal operation, said pan being provided with a slot extending diametrically inwardly through the flange and dished bottom portion and terminating in the latter, said terminal portion substantially filling the slot and defining with the dished bottom portion of the pan, a heat-reflecting drip receptacle, and a plate secured to the depending terminals of the heating element and extending radially outwardly above said flange for covering the portion of said slot which traverses the flange, said pan

being removable from the heating element and the terminal shield in the direction of the slot when the heating element and shield are raised above their normal working positions.

5. In a heating structure for a range platform, the combination of a substantially circular heating element having a flat heating surface and depending terminal portions, a unitary pan comprising a circular side wall, a flange projecting radially outwardly from the upper end of the side wall and a bottom wall extending across the lower end of the side wall, said flange encompassing the heating element and removably engaging the range platform for supporting the pan in normal position, said pan being provided with a slot extending diametrically inwardly through the flange, side wall, and bottom wall of the pan and said slot terminating in the bottom wall of the pan, a shield secured to the depending terminal portions of the heating element, said shield being formed to close the slot in the bottom wall of the pan, whereby the shield and pan define a substantially uninterrupted, heat-reflecting drip receptacle, said pan being removable from the heating element and the terminal shield in the direction of the slot when the heating element and shield are raised above their normal working positions, and a radially-extending plate movable with the heating element and covering the portion of the slot in said flange.

6. In a heating structure for a range platform, the combination of a substantially circular heating element having a flat heating surface and depending terminal portions, a unitary pan comprising a circular side wall, a flange projecting radially outwardly from the upper end of the side wall and a bottom wall extending across the lower end of the side wall, said flange encompassing the heating element and removably engaging the range platform for supporting the pan in normal position, said pan being provided with a slot extending diametrically inwardly through the flange, side wall, and bottom wall of the pan and a shield secured to the depending terminal portions of the heating element, said shield being formed to close the slot in the bottom wall of the pan, whereby the shield and pan define a substantially uninterrupted, heat-reflecting drip receptacle, and a projection carried by said shield and spaced below the bottom wall of the pan in the normal position of the heating element, said projection being engageable with the bottom wall of the pan for raising the latter when the heating element and shield are moved upwardly, said pan being removable from the heating element and the terminal shield in the direction of the slot when the heating element and shield are raised above their normal working positions.

7. In a heating structure for a range platform, the combination of a substantially circular heating element having a flat heating surface and depending terminal portions, a unitary pan comprising a circular side wall, a flange projecting radially outwardly from the upper end of the side wall and a bottom wall extending across the lower end of the side wall, said flange encompassing the heating element and removably engaging the range platform for supporting the pan in normal position, said pan being provided with an open end slot extending diametrically inwardly through the flange, side wall, and bottom wall of the pan, a shield secured to the depending terminal portions of the

heating element, said shield being formed to close the portion of the slot in the bottom wall of the pan, whereby a substantially uninterrupted, heat-reflecting drip receptacle is defined, said pan being removable from the heating element and the terminal shield in the direction of the slot when the heating element and shield are raised above their normal working positions, and a plurality of spaced supports movable with the heating element and shield and engageable with the platform for supporting the heating element and shield in the elevated position of the heating element and shield.

8. In a heating structure for a range platform, the combination of a substantially circular heating element having a flat heating surface and depending terminal portions, a unitary pan comprising a circular side wall, a flange projecting radially outwardly from the upper end of the side wall and a bottom wall extending across the lower end of the side wall, said flange en-

compassing the heating element and removably engaging the range platform for supporting the pan in normal position, supporting means carried by the side wall of said pan, a plurality of radially-extending projections carried by the heating element and engageable with said supporting means in the normal position of the heating element, said pan being provided with an open end slot extending diametrically inwardly through the flange, side wall, and bottom wall of the pan and a shield secured to the depending terminal portions of the heating element, said shield being formed to close the slot in the bottom wall of the pan, whereby a substantially uninterrupted drip receptacle is defined, said pan being removable from the heating element and the terminal shield in the direction of the slot when the heating element and shield are raised above their normal working positions.

WILLIAM J. RUSSELL.
